WALFRED GERHARD SWANSON, OF SWANVILLE, MINNESOTA

CREAM CAN HOLDER

Application filed May 21, 1930. Serial No. 454,465.

This invention relates to certain new and useful improvements in holders for milk cans and the like for maintaining same submerged in a cooling chamber.

- 5 One of the principal objects of the invention consists of can engaging means designed to maintain the submerged can in an upright position to obviate spilling or loss of the contents.
- 10 An additional object of the invention contemplates the provision and arrangement of a locking mechanism for this purpose.

15 A further object of the invention embodies a releasing means for the locking mechanism operable from a point above the liquid level in the cooler.

20 With the above and other objects in view, the invention further consists of the following novel features and details of construction, to be hereinafter more fully described, illustrated in the accompanying drawing and 25 pointed out in the appended claim.

In the drawing:

25 Figure 1 is a fragmentary elevation of a cooling compartment illustrating the particular mounting and relationship of the invention when applied for use.

30 Figure 2 is a top plan view of the invention as applied.

35 Figure 3 is a detail sectional view taken through the immediate portions of the can holding means, locking mechanism and releasing means.

40 Referring to the drawing in detail wherein like characters of reference denote corresponding parts, the reference character 10 indicates generally a tank, vat or other receptacle for containing a body of water, quantity of ice or the like found suitable for the

45 purpose of maintaining milk at a safe temperature. Heretofore milk or other cans partially submerged in solutions of this character were held down, or in submerged positions by swingably mounted supports arranged at intervals upon the walls of the vat.

50 These holders would serve their purpose well if a number of these cans were so arranged in the vat as to abut one another and obviate tilting, but in the event it was desired to remove any one of the cans, the space originally

occupied by the removed can would be immediately taken up by the remaining shifting cans which would then bob up in the vat, topple over and either spill the contents thereof or permit water seepage. The present invention is designed to overcome these previous experiences by arranging individual holders for each of the several cans in the one vat, whereby any one of the cans can be separately removed and replaced without interfering with the other cans.

55 In carrying out my invention, I provide attaching plates 11 arranged at suitable heights within the vat and upon the walls thereof in the manner suggested in Figure 1 60 of the drawing. The ends of each of the attaching plates are offset at right angles to provide long and short ears 12 and 13 respectively. A rod member 14 slidably accommodated within aligned openings provided in 65 the aforementioned ears is offset as at 15 upon its uppermost end above the ear 13.

70 A hoop or can neck receiving portion 16 carried upon the offset portion 15 of the slidably mounted rod 14 is designed to accommodate the neck of the commercial size or shape of milk can 17 and to repose against the shoulder thereon formed between the can body proper and the neck. An extension 18 carried by and upstanding from the outermost projecting end of the ear 12 is apertured to accommodate the tongue 19 of a horizontally positioned rockingly mounted locking plate 20. The latter is drilled or otherwise provided with an obliquely inclined opening 21 exposing the marginal edges at the ends thereof for biting engagement with the immediate portions of the rod member 14 passed therethrough.

75 A releasing rod 22 slidably mounted within openings provided in the ears 12 and 13 and the locking element 20 carries a boss 23, an adjusting nut 24 and a boss 25 for engagement with the adjacent guides mentioned in order. The boss 23 will restrict downward movement of the releasing lever 22, the nut 24 may be adjusted to restrict motion of the lever in an upward direction and the boss 25 is designed for contacting engagement with the upper side and free end of the rockingly 80 85 90 95 100

mounted locking plate 20 to free the latter from biting engagement with the rod member 14. A compression spring 26, carried by and encircling that portion of the releasing rod 22 between the ear 12 and the locking plate 20, and sprung at its ends against the latter, will normally and yieldingly maintain the locking plate 20 in the positions shown in Figures 1 and 3 of the drawing for biting engagement with the rod member 14 whereby the latter will be maintained in operative position, as shown in Figure 1.

An eye or finger engaging portion 27 is formed upon the uppermost end of the releasing rod 22 by means of which the operator may readily shift the same to occupy the different positions necessary to facilitate removing and replacing of the milk cans.

Although I have shown and described my invention employed for the purpose of holding milk cans partly submerged in cooling vats, it is obviously apparent that I do not restrict or limit myself to this particular use as many other possible uses will suggest themselves.

The invention is susceptible of various changes in its form, proportions and minor details of construction and the right is herein reserved to make such changes as properly fall within the scope of the appended claim.

Having described the invention, what is claimed is:

In combination with a water tank and a can, means for holding the can in upright position in the tank when immersed in the water therein comprising a guide mounted upon the wall of the tank, a rod slidably mounted in the guide and having at its upper end a hoop adapted to engage over the shoulder of the can, means mounted upon the guide for locking the rod and hoop at a lowered position and means within the tank for releasing the rod locking means.

In testimony whereof I affix my signature.

45 WALTER GERHARD SWANSON.
